UNITED STATES PATENT OFFICE

2,580,676

BOTTLE RACK

Arthur R. Gross, St. Paul, Minn.

Application August 13, 1948, Serial No. 44,000

1 Claim. (Cl. 211—74)

1
My invention relates generally to bottle-holding racks, and, more specifically, to racks for holding bottles adapted to contain carbonated beverages and the like.

Racks of this type, which are generally used to hold empty bottles and which are usually associated with automatic coin-operated bottle-dispensing devices, have hitherto been provided with built-in shelves. Such racks are usually heavy and cumbersome, and frequently the shelves thereof become catch-alls for bits of waste paper, cigarette butts, and other litter. Therefore, a highly important object of my invention is the provision of a bottle rack which is inexpensive to manufacture, which is extremely light in weight, which is devoid of internal bottle-supporting shelves, and which is rugged in construction and durable in use.

Another highly important object of my invention is the provision of a rack as set forth having a front wall and a back stop wall element, the front wall having a plurality of apertures each of a size to admit the base and maximum diameter body portions of a bottle of given dimensions, the upper and lower edges of said apertures engaging the body portions of the bottles outwardly of the centers of gravity thereof, and a back stop wall element engaging the bases of the bottles.

Other important objects and advantages will become apparent from the following detailed specification, appended claim, and attached drawings.

Referring to the drawings, wherein like characters indicate like parts throughout the several views:

Fig. 1 is a view in front elevation of my improved bottle rack;

Fig. 2 is a vertical section taken on the line 2—2 of Fig. 1;

Fig. 3 is a transverse section taken on the line 3—3 of Fig. 1; and

Fig. 4 is a view corresponding to Fig. 3, but showing a modified form of the invention.

In the preferred embodiment of the invention illustrated in Figs. 1-3 inclusive, my improved rack is shown as being in the nature of a hollow rectangular structure having a vertically-disposed front wall 1, integrally-formed side walls 2, and a back stop wall element in the form of a solid wall 3. The back wall 3 is provided at its opposite side edge portions with rearwardly-projecting flanges 4 which are rigidly secured to the rear edge portions of the side walls 2 by spot welding or the like. A top wall section 5 is pro-

2
vided with a down-turned flange 6 which engages the top edge portion of the front and side walls 1 and 2 respectively and is rigidly secured thereto by spot welding or the like. The upper end of the back wall 3 is formed to provide a rearwardly-projecting flange 7 which is welded to the top wall 5 adjacent its rear edge. The rear edge portion of the top wall 5 is formed to provide a down-turned flange 8 which is adapted to be seated in an upwardly-opening hook 9 secured to the side of a coin-controlled automatic bottle-dispensing machine 10. The dispensing machine 10 is diagrammatically-indicated by dotted lines in Fig. 2, and forms no essential part of the invention herein disclosed except to provide a supporting means therefor.

A generally rectangular bottom wall 11 is formed with a peripheral flange 12 which is spot welded to the lower end portions of the front wall 1, side walls 2, and rear wall 3. The bottom wall 11 is provided with a plurality of relatively large circular openings 13, the purpose of which will hereinafter become apparent. A pair of supporting legs 14 are welded or otherwise secured to the flange 12 in opposite rear corners of the bottom wall 11, and provide supporting means for the rack when no supporting means such as the hook 9, on the machine 10, is available. The back wall 3 is provided with stiffening ribs 15 and 16 which are spot welded thereto and extend transversely of the rack. It will be seen by reference to Fig. 2 that the rib 16 extends rearwardly of the rack, and when said rack is suspended on the up-turned hook 9 a slight rearward inclination is imparted to the rack.

The front wall 1 is provided with a plurality of bottle-receiving apertures 17. Said apertures 17 are preferably circular and of a size to admit the bases and maximum diameter body portions of bottles of given dimensions. Apertures 17 are defined by annular flanges 17a which provide smooth passage of bottles therethrough. In the embodiment illustrated, the rack is adapted to receive bottles of a shape peculiar to a nationally advertised and distributed beverage, said bottles being indicated by the numeral 18, and comprising base portions 19, maximum diameter body portions 20, and neck portions 21. The rear wall 3 is spaced from the front wall 1 to admit the greater portion of the bottle 18, see particularly Fig. 2. When one of the bottles 18 is inserted into the rack to the extent permitted by the engagement of the base 19 thereof by the back wall 3, the plane of the vertical front wall 1 will lie outwardly of the center of gravity of

the bottle 18. The maximum diameter body portion 20 of the bottle 18 will be engaged by upper and lower edge portions 22 and 23 respectively of the aperture 17, said engagement permitting limited downward tilting movement of the body and base portions of the bottle 18 within the rack 1. The engagement of the bases 19 by the back wall 3 and the body portions 20 thereof by the upper and lower edge portions 22 and 23 of the apertures 17 provides, in effect, a three-point suspension for the bottles 18.

I provide a plurality of stiffening ribs in the nature of angle bars 24 secured by welding or the like to the inner surfaces of the front wall 1. The ribs 24 extend transversely of the front wall 1 between adjacent rows of bottle-receiving apertures 17. It will be seen by reference to Fig. 2 that the ribs 24 extend rearwardly but a relatively short distance, and that the interior of the rack is otherwise unobstructed from the top wall 5 to the bottom wall 11 thereof. I have found that racks having vertically-spaced horizontally-extended bottle-receiving shelves have had the shelves thereof cluttered with bottle caps, matches, and other litter thrown thereinto by careless persons. Any such foreign matter which may be admitted through the apertures 17 will fall by gravity to the bottom wall 11 thereof and be discharged through the openings 13 in said wall 11.

In the modified structure illustrated in Fig. 4, a back stop wall element is shown as being in the nature of a plurality of spaced stop strips 25 preferably formed from angle iron or the like. The strips 25 extend from the bottom wall 11 to the top wall, not shown, and are disposed one each intersecting the rearwardly-projected axes of one of the vertical rows of apertures 17 in the front wall 1. Except for the substitution of stop strips 25 for the solid back wall 3, the structure of the rack is identical to that illustrated in Figs. 1-3 inclusive, like parts being designated by like numerals with prime marks added.

The rack herein described is particularly adapted for use with bottles of the kind illustrated, but may be used to contain and store other bottles having substantially the same dimensions. Obviously, for larger or smaller bottles, the diameter of the apertures 17 and the distance between the front wall 1 and the back wall 3 must be commensurate with the size of said bottles.

My invention has been thoroughly tested and found to be entirely adequate for the fulfillment of the objectives set forth, and while I have disclosed a preferred embodiment and a single modification thereof, it will be understood that the same is capable of further modification within the spirit and scope of the invention as defined in the claim.

What I claim is:

10 A rack for holding cross-sectionally circular bottles of given dimensions comprising a generally vertical front wall having a plurality of circular bottle-receiving apertures, and a back stop wall element in spaced parallel relation to said apertured wall, each of the apertures being of a diameter to admit the base and maximum diameter body portions of one of said bottles, the spacing of said apertured wall and said back stop wall element with respect to the length and shape of the bottles being such that the upper and lower circular edge portions of said apertures engage said bottles outwardly of the centers of gravity thereof, whereby said bottles will tilt downwardly within said rack, the bases of said bottles engaging said vertical back stop wall element, said upper and lower edge portions of the apertures and said vertical wall element constituting the sole means of support for said bottles.

30 ARTHUR R. GROSS.
